STOP MOTION FOR SPEEDERS AND THE LIKE

Weaver W. Tripp, Mebane, N. C.

Application June 20, 1932. Serial No. 618,390

6 Claims. (Cl. 118—5)

This invention relates to means for automatically stopping roving frames, drawing frames, spinning frames, and the like such as speeders and the like from automatically stopping the machine when a certain number of layers of yarn have been wound onto the packages of yarn such as bobbins in a speeder.

It is an object of this invention to provide additional means driven by the speeder and the like whereby the stop motion mechanism which is conventional in the speeder and the like will be automatically operated when a definite amount of yarn has been wound onto the packages such as bobbins and the like.

It is an object of this invention to provide a stop motion for speeders and the like whereby the speeder and the like can be stopped when the builder motion is applying yarn to the middle portion of the packages whereas in conventional stop motions the stoppage occurs when the yarn is being applied to the end portions of the packages of yarn. By use of my improved stop motion, the first layer of yarn can be begun midway, for example, of the packages of yarn and fed downwardly first, then to the top of the package and then down to the bottom of the package which operation is repeated until the required number of layers of yarn has been wound onto the packages and then the machine can be stopped at a time when the yarn is being applied midway of the packages, thus giving two extra layers of yarn to the lower half of the package.

By my stopping the applying of the yarn at the midway point on the packages, distinct advantages in doffing are obtained.

By use of my improved stop motion the carriage for the builder motion in speeders and the like can be stopped while moving downwardly or upwardly.

By adjustment of sprocket 30 on shaft 27c, the builder mechanism can be stopped at any desired point on the packages.

Some of the objects of the invention having been stated, other objects will appear as the description proceeds when taken in connection with the accompanying drawings, in which—

Figure 1 is an enlarged elevation showing the invention applied to a portion of a speeder and the like;

Figure 2 is a transverse sectional view taken along the line 2—2 in Figure 1;

Figure 3 is a vertical sectional view taken along the line 3—3 in Figure 1;

Figure 4 is an elevation of the sprocket and associated parts forming a part of my invention;

Figure 5 is an enlarged exploded elevation of the structure shown in Figure 4;

Figure 6 is an enlarged transverse sectional view taken along the line 6—6 in Figure 4;

Figure 7 is an enlarged sectional view taken along the line 7—7 in Figure 4.

Referring more particularly to the drawings, the numeral 10 indicates one of the samsoms of the speeder and the like to which is secured a suitable plate 11 having a hole 12 therethrough in which is adapted to operate knock-off latch 13 to which is secured a chain 14 for operation of stop motion mechanism and other features which is not a part of the invention. Secured to plate 11 is a bracket 15 having bolts 16 and 17 penetrating slots 18 and 19 respectively for securing bracket 15 to samson 10. Bracket 15 has downwardly projecting portion 20 and upwardly projecting portion 21, said upwardly projecting portion having a suitable transverse bore therein with a set screw 22 penetrating the portion 21 and extending into said bore. Rotatably mounted in said bore is a bearing member 24 having a groove 25 therein adapted to receive the end of the bolt 22. This bearing 24 has a transverse slot 25a therein and at the other end thereof, has an extension 26 having a slot 27 therein. Bearing member 24 has a bore extending longitudinally thereof in which is rotatably mounted a shaft 27c having an enlargement 28 on the end thereof of the same size as the portion 26 on bearing member 24 and a slot 29 is provided in said member which, at times, is adapted to mesh with slot 27.

Shaft 27c is adapted to have fixedly secured thereon a sprocket wheel 30 by means of set screw 31 and this sprocket wheel 30 has integral therewith a tongue 32 adapted to fit into slot 25a.

Member 20 has a vertically disposed slot 35 therein in which the bolt 36 is mounted which also penetrates slot 37 in L-shaped member 38 which is forked at its upper end and in fork 39 is mounted a compression spring 40 adapted to press against the lower side of a lever 41 which lever is pivotally mounted as at 42 in fork 43 of member 38. Lever 41 has end portion 45 having set screw 46 therein which secures shaft 47 therein and on shaft 47 is loosely mounted a gear wheel 48 having a pin 49 therein. Loosely mounted on shaft 47, said shaft 47 being headed as at 50, is a vane 51 which is adapted to be raised by pin 49 to press against knock-off latch 13 to automatically stop the machine and after passing above dead center at the top, vane 51 falls downwardly to assume a neutral position ready to be overtaken by pin 49 and raised again.

Portion 26 also has a slot 27a on the opposed side thereof which is ordinarily not used but which can be used in conjunction with slot 29 if desired. Sprocket wheel 30 is adapted to have mounted thereon a sprocket chain 55 which is also mounted on a sprocket wheel 56 120

fixedly mounted on the carriage lifter shaft 57 driven by the machine so that sprockets 56 and 30 together with sprocket chain 55 are oscillated at all times, as shaft 57 has an oscillatory motion imparted thereto by the machine.

If a clockwise direction is desired to be imparted to wheel 48 as shown in Figure 2, the parts are adjusted in the position shown in Figure 5 and in this position tongue 32 is pressing against the upper sidewall of slot 25a and slots 29 and 27 are in alignment and one of the teeth in gear wheel 48 falls into both slots 27 and 29 and the entire assembly of Figure 5 is moved further in clockwise direction in Figure 2 and moves gear wheel 48 one tooth. But as the mechanism is reversed and shaft 57 moves in the opposite direction then tongue 32 must move to the lower side of slot 25a in Figure 5 before bearing member 24 is moved and in so doing shaft 27c moves with sprocket 30 and tongue 32 and, therefore, slot 29 is out of alignment with slot 27 and gear wheel 48 being as broad as both members 26 and 28 the teeth of gear wheel 48 do not become engaged with either slot 29 or 27 and the gear wheel is not moved at all, but when the shaft 27c is moved again in a clockwise direction as seen in Figure 2, slots 29 and 27 will coincide when tongue 32 engages the upper side of slot 25a to move bearing member 24 and these two slots 27 and 29 being aligned will allow gear 48 to fall thereinto and allow the gear to be moved one tooth. The gear is gradually moved and pin 49 engaging vane 51 gradually raises the vane upwardly until it engages knock off latch 13 to raise it upwardly in hole 12 to allow it to become disengaged from the lower edge of hole 12 and the conventional mechanism in the machine will move the knock off latch to the right in Figure 1 and automatically stop the machine.

In this manner the exact amount of yarn to be wound onto the packages in a speeder and the like can be regulated and the knock-off motion will automatically operate at predetermined times.

Gear wheel 48 is interchangeable, it being understood that this gear wheel 48 has a number of teeth therein agreeing with the number of layers of yarn on the packages.

Sprocket wheel 56 moves in one direction while the builder motion of the machine is moving upwardly, and in a reverse direction when builder motion is moving downwardly so wheel 48 is moved one tooth for each two layers of yarn placed on the packages.

In the drawings and specification, there has been set forth a preferred embodiment of the invention and although specific terms are employed, they are used in a generic and descriptive sense only and not for purposes of limitation, the scope of the invention being set forth in the appended claims.

I claim:

1. In a yarn package forming machine such as a speeder and the like having an oscillating carriage lifter shaft and a knock off latch and means connected to the knock off latch for moving it to stop the machine and also having means for holding the knock off latch in a position to allow the machine to operate, a gear

wheel movable step by step by the oscillating carriage lifter shaft, and separately movable means pivoted on the same center as the gear wheel and engageable by the gear wheel for moving said knock off latch to stop the machine after said oscillating shaft has oscillated a given number of times.

2. In a fiber preparation machine having yarn package forming means including a builder motion reciprocable vertically with relation to the packages of yarn, a knock off latch and an oscillating carriage lifter shaft, a gear wheel movable by alternate oscillations of the carriage lifter shaft, and means separate from but pivoted on the same center as the gear wheel engageable by said gear wheel for engaging the knock off latch to stop the machine.

3. In a fiber preparation machine having a yarn package forming means including a builder motion reciprocable vertically with relation to the packages of yarn, a knock off latch and an oscillating carriage lifter shaft, a gear wheel movable by alternate oscillations of the carriage lifter shaft, and means pivoted on the same center as the gear wheel engageable and movable by said gear wheel means for engaging the knock off latch to stop the machine.

4. In a stop motion device for package forming machines for yarn and the like having a builder motion controlled by a knock off latch and having an oscillating carriage lifter shaft for operating the builder motion, a gear wheel, means connected with the said shaft for advancing said gear wheel step by step in one direction, means pivoted on the same center as the gear wheel but separated from the gear wheel and, movable by the wheel for moving said knock off latch to stop the machine and means for adjusting the means for moving the wheel to stop the machine while the carriage is applying yarn to the packages at a point intermediate the ends of the packages.

5. In a stop motion device for package forming machines for yarn and the like having a builder motion controlled by a knock off latch and having an oscillating carriage lifter shaft for operating the builder motion, a gear wheel, means connected with the said shaft for advancing said gear wheel and a vane pivoted freely on the same center as the gear wheel and movable against gravity by the gear wheel for moving said knock off latch to stop the machine.

6. In a stop motion for package forming machines for yarn and the like and having a builder motion controlled by a knock-off latch and having an oscillating carriage lifter shaft operable in timed relation to the builder motion, a gear wheel, a shaft for rotatably supporting the gear wheel, means driven by the oscillating shaft for advancing the gear wheel in one direction, a member pivotally mounted at one of its ends on said gear wheel shaft, means on the gear wheel for engaging said member for raising the free end of said member to cause said member to engage and move the knock-off latch, said member after being moved past dead center by the means on the gear wheel being adapted to fall by gravity and to be overtaken by the means on the gear wheel.

WEAVER W. TRIPP. 145
